ELEVATOR SAFETY DOOR LOCK

Herbert Allen Rainey, Richmond, Va.

Application April 10, 1939, Serial No. 267,123

3 Claims. (Cl. 187—57)

This invention relates to elevator door safety locks; and more particularly, to such devices which are placed on the inside of the elevator shaft and which in the normal operation will only allow the door to be opened when the elevator car is standing at the floor.

Numerous devices have been perfected for locking elevator doors so as to preclude possibility of persons walking into an elevator shaft when a car is not at the floor. Although these devices have to a large extent operated satisfactorily, there are occasions when faulty conditions of one sort or another have permitted the doors to be opened, or left open, resulting in serious accidents.

One object of this invention is to provide an elevator door safety lock mechanism which will positively preclude the opening of the elevator door unless a car is stopped at the floor, except in cases of emergency.

Another object is to provide a safety lock system which is adapted to be applied to existing elevator systems without in any way interfering with the operation of the existing apparatus.

Another object is to provide a safety mechanism of very simple construction.

Other objects and advantages of this invention will appear from the following description taken in connection with the accompanying drawings.

In the drawings, wherein like characters represent corresponding parts in the various figures—

Figure 1 is a partial elevation showing the mechanism on the inside of an elevator shaft as viewed facing the door;

Figure 2 is a transverse section substantially on the line 2—2 of Figure 1;

Figure 3 is a further view similar to Figure 1, but showing the parts in a position with the door open; and

Figure 4 is an enlarged detail of a part of the safety locking mechanism.

Considering the drawings in greater detail, one set of elevator doors 10 and 11 are shown which form the closure elements of the door opening 12

located at any floor of a building. The door 11 is normally closed at all times, and may be secured adjacent the door openings by either hinges or a sliding connection. The door 10 is allowed to slide back and forth thereby opening and closing the entrance 12 to the elevator shaft.

This movable door is shown as being mounted by rollers 13 and 14 for sliding connection on the supporting shaft 15, and may also have rollers 16 and 17 at the bottom thereof supporting the door in a groove or runway 18. The

door is normally locked closed by the levers 19 and 20 which are pivotally connected together at the point 21, and which are pivoted, respectively, at 22 on the door and at 23 to a bracket 24 properly secured at 25 to the side wall 26 of the elevator shaft. It will be obvious that with the door in the position shown in Figure 1, a limit stop 27, carried on the lever 19, engages the lever 20 to stop the levers in horizontal position. In order to open the elevator door, it is necessary to raise the levers out of their dead center position.

In order to prevent the door from slamming at the limit of either opening or closing movement, a pair of dash pots 28 and 29 are connected with the lever mechanism just described by appropriate linkages so as to dissipate the momentum of the door with an appropriate cushioning action. The dash pots are pivotally supported, at 30 and 31, on a bracket 32, which latter is secured in the wall 26. A bracket 33 is secured to the wall of the elevator shaft, and supports at its outer end a lever 34. The lever 34 is pivotally connected to the piston rods 36 and 37 and is pivotally supported on the bracket at 35 for oscillating movement. The dash pots may be of any appropriate construction, and may preferably be of liquid dash pot type.

The outer end of lever 34 has a pivotal connection with the upwardly extending connecting rod 39, which latter is pivoted at 40 upon a cross head 41. The cross head is also connected to the lever 20 by way of a bracket 42. This connection is accomplished by an intermediate link 43 pivotally connected on the cross head at 44 and on the bracket at 45.

It will be observed that as a result of this system of linkages, that at least one or the other of the dash pots will take up the momentum of the door at the end of its closing or opening movement. An additional means for absorbing the shock of opening the door is obtained with the bumper 46 which may be of rubber or other suitable material.

Instead of having to rely solely upon the manual power exerted by the elevator operator in grasping the door hand grip 47 to open it, power means can preferably be provided to reduce the manual effort needed. In this respect a power cylinder 48 is mounted on the bracket 49, and is connected to the linkage system in such a manner that the power means is normally biased to the position locking the door shut. Differential springs 50 and 51 engage the end of the cylinder 48 and the piston 53, respectively. The other

ends abut against the collar 52 sliding substantially centrally on the piston rod 54. The upper end of this rod 54 is secured to cross head 41, which ties the power cylinder into the linkage mechanism. The springs 50 and 51 are arranged with differential spring tension; and the cylinder may preferably be pneumatically operated, but it will be understood that other fluid mediums may be utilized. The cross head 41 is firmly secured to the guide rod 55, which latter slides in bearings 56 and 57 carried by the brackets 58 and 49, respectively. The bracket 58 is also apertured at 59 to allow the securing means 60 to pass through the bracket without striking against the same. In this manner a reasonable amount of adjustment can be obtained without requiring a relocating of any of the parts.

The operation of the power means is controllable by the operator of the elevator passing through the shaft, and is only placed in operation as a result of the car stopping at a particular floor. In order to accomplish this, a cam 61 is carried by the supporting element 62 upon the elevator car. This cam is normally positioned on the elevator car so as to avoid striking or engaging the roller 63. When the car is being stopped for a particular floor, the elements 62 are moved as a result of the operator throwing the car controls for a stop, with the result that the cam surface engages the roller 63, in turn causing the bell crank 64 to move from the full line position of Figure 1 to the full line position of Figure 3. This movement is transmitted to the control valve 65 by way of the valve stem lever arm 66. Fluid supply enters the valve by the connection 67, and, with the valve in operating position as seen in Figure 3, fluid is allowed to enter the cylinder to push the piston 53 upward transmitting its thrust through the piston rod 54, cross head 41, and link 43 to open the elevator door. The movement of the bell crank is transmitted at the valve arm 66 by way of the push rod 68, which latter, at its lower end, is connected to the bell crank by a yoke 69 and pin connection 70, the bell crank having a slot 71 to provide a certain amount of lost motion, so that there will not be any binding of the parts in operation. The push rod carries a collar 72 and the spring 73 is interposed between the collar 72 and the bracket 74, thereby urging the spring downwardly to reset the mechanism in door locking position.

The movable door is arranged to be latched open by means in addition to that heretofore described, including the pivoted latch member 75 and the movable abutment 76. The latch is mounted on a boss 77 carried by plate 78, which latter carries two limit stops 79 and 80, respectively, the former preventing the latch from being completely turned on its pivot, the latter serving to stop the door when the latch is thrown against the movable abutment 76. The pivotal arrangement of this latch allows the door moving past the abutment 76 to be moved back into closing position with the latch riding up on the abutment and dropping back into place, as indicated in Figures 1 and 3. This latch can preferably be weighted to hold it in its normal position. The abutment 76 being mounted with respect to the floor, and being positioned a short distance away from the latch, will allow the elevator door to be opened a very narrow space, for example, an inch more or less. In cases of emergency this will allow the person to observe in

elevator shaft without being able to open the door far enough to create a hazard.

The movable abutment 76 has a lower angular cam surface 81 which slides upon the cam surface 82 in the central slot of the abutment base 83. The base is secured to the floor structure as indicated. The abutment is indicated in its normal door locking position in Figure 1, and is moved to the left in Figure 3, thereby allowing the latch 75 to ride above it. The movement of the abutment is accomplished by the push rod 84, which is pivoted at 85 to the abutment. The opposite end of the push rod is pivoted at 86 to one arm 87 of a bell crank 87, the latter being pivotally supported at 88 on the floor. The opposite arm 89 of the bell crank 89 is arranged with a slot and pin connection similar to the one 79-71 on the previously described bell crank. Both of these connections are to the yoke 69.

It will now be observed that at the same time the elevator car cam 61 moves the bell crank 64 to apply power to open the door, it also operates the mechanism moving the abutment 76 to release the door safety lock.

It will now be observed that even if a leak should occur in the valve 65 allowing pressure to build up in the operating cylinder 48, the latch and abutment 75-76 will positively preclude the opening of the elevator door. Since there is no direct connection between the safety lock mechanism and the power mechanism, either may operate independently of the other and still preserve the safety locking feature with regard to the door. In case of an emergency where it is absolutely necessary to force the elevator safety door open, an aperture 90 is arranged in the normally closed door and the arm 91 is secured on the push rod 84. A suitable tool 92 can be inserted in this hole to act as a lever engaging the arm 91 with the leverage being sufficient to release the door safety latch.

Although a preferred embodiment of this invention is illustrated and described, variations within the true spirit and scope of the same are to be determined by the appended claims.

What I claim is:

1. In association with a slidable elevator door a latch pivoted on the shaft face of the door near its bottom with means to limit its rotation and a stop for the latch mounted on the door sill comprising a fixed member provided with a slot having an inclined bottom and a movable member having a depending flange slidable in said slot, said flange having an inclined bottom and means for sliding the movable member with respect to the fixed member, whereby the height of said stop can be adjusted.

2. The device of claim 1 in which the means for sliding the movable member of the stop includes a connecting rod extending adjacent the door, and having a lug, the elevator door being provided with an orifice adjacent said lug whereby the connecting rod can be manipulated by a rod inserted through said orifice.

3. The device of claim 1 with power operated mechanism for sliding the door including means for controlling the power and means connecting said power controlling means with the movable member of the stop whereby the application of power to the door operating mechanism will simultaneously slide the movable stop member out of the path of the pivoted latch.

HERBERT ALLEN RAINY.
